(57) **CLAIM**

The ornamental design for latch for snips, as shown and described.

DESCRIPTION

FIG. 1 is a perspective view of a latch for snips showing my new design;

FIG. 2 is a front view thereof;

FIG. 3 is a left view thereof;

FIG. 4 is a right view thereof;

FIG. 5 is a top view thereof;

FIG. 6 is a bottom view thereof; and,

FIG. 7 is a perspective view showing the latch for snips residing in a pair of snips. The broken line showing of the snips in FIG. 7 illustrates the environment of the claimed design and forms no part thereof.

1 Claim, 6 Drawing Sheets**FIG. 1**

FIG. 2

FIG. 4

FIG. 3

FIG. 5

FIG. 6

FIG. 7
